UNITED STATES PATENT OFFICE.

HOSMER TUTTLE, OF CEDAR RAPIDS, IOWA, ASSIGNOR OF ONE-HALF TO
SHELLEY TUTTLE, OF SALT LAKE CITY, UTAH.

BICYCLE.

SPECIFICATION forming part of Letters Patent No. 650,346, dated May 22, 1900.

Application filed February 19, 1898. Serial No. 670,945. (No model.)

To all whom it may concern:

Be it known that I, HOSMER TUTTLE, a citizen of the United States, residing at Cedar Rapids, in the county of Linn and State of Iowa, have invented certain new and useful Improvements in Bicycles, of which the following is a specification, reference being had therein to the accompanying drawings.

My invention relates to mechanical movements intended mainly for the propulsion of bicycles to take the place of the chain now generally used on safety-bicycles, and thereby reduce the expense and the amount of friction.

Although the construction of the movement can be used in connection with other machines it is shown in the drawings in connection with a bicycle, the frame of which may be of any suitable form. It comprises cranks and crank-pins on the axle of the hind wheel, sprocket-wheels on the axle of the pedal-shaft, and forked connecting-rods to unite said axles, as described in Patent No. 564,665, granted to me July 28, 1896; but in this improvement the location of the hind crank is within the side frames, the interlocking sprockets are provided with antifriction-rollers, and the ends of the forked connecting-rods are provided with hooked connections adapted to rock on said ends, said hooked rocking connections having a segment of gear-teeth on their outer periphery in engagement with short stationary racks to cause their rocking and facilitate the noiseless entrance of the sprocket-rollers into the hooked rocking connections and their issue therefrom and also to compensate for the inequalities of speed of the connecting-rod due to the rear crank's motion, and thus obtain uniform motion of the sprocket-wheel.

Other new features will be described in connection with the accompanying drawings, in which—

Figure 1 represents a side view of a bicycle provided with a mechanism constructed in accordance with my invention, but showing only one of the forked rods. Fig. 2 represents, on a larger scale, a top view, partly in section, of the mechanism. Fig. 3 represents a side view of the mechanism on one side of the machine, with the casing of the

sprocket-wheel in section. Fig. 4 represents a horizontal section of a portion of one of the cranks, its shaft, the sprocket-wheel secured thereto, the sleeve of the crank-shaft, and the casing secured thereto. Fig. 5 is a side view of one of the ball-bearing locking-sleeves and its locking-bolt. Fig. 6 is an end view of the locking-sleeve. Fig. 7 is a side view of one of the hooked rocking connections of one branch of one of the forked connecting-rods, its side arm being broken off to show its slot. Fig. 8 is a transverse section of said hooked rocking connection mounted upon one branch of one of the forked connecting-rods. Fig. 9 represents an end view of said hooked rocking connection having its groove or hook in engagement with one of the rollers of the sprocket-wheel and its toothed upper end in engagement with the rack secured to the casing. Fig. 10 represents, in top view and partly in section, the rear-wheel axle, its ball-bearings, crank-shaft, and connecting-rods. Fig. 11 is a side view of the rear portion of one of the forked rods, its crank-pin, ball-bearing cone, and locking device for said cone. Fig. 12 is a perspective view of the crank-pin.

In said drawings, A represents the seat-carrying standard of the frame, and A² the braces between the crank-shaft b, carrying the pedals B² and also the sprocket-wheels C and C², and the crank-axle d for the hind wheel E, said axle d having its ends received in ball-bearings a², mounted in the rear ends of the braces A² and protected by caps a³, which serve also as a lock-nut for the ballway.

Each end of the axle d has a crank-arm d², and each end of the hub of the wheel E has a similar crank-arm e², but the arms e² are set at an angle of ninety degrees to each other. The arms d² e² of each crank are united together by a tubular crank-pin D, having four lugs provided with side faces that are not radial, but are parallel or at right angles to each other and are projecting from each one of its ends that are received in corresponding grooves formed at right angles to each other in bosses on the arms d² e², and a bolt D², passing through said arms and through the crank-pin D, secures these parts together until it is desired to remove the wheel E for repairs or until it is desired to have the crank-pin occupy

- a position a quarter of a revolution front or back to make up for wear of the parts. The pin D is grooved circumferentially to obtain a ballway to receive the inner face of the 5 balls of the ball-bearing around it, and said balls are inclosed by the rear end of each forked connecting-rod, being adjustably retained in their seat by a ball-cone D³, having its periphery provided with serrations. To 10 lock said cone a dog d³ is secured with a screw to the outer face of each connecting-rod and has its acute end made to engage with some one of the serrations on the periphery of the flange of the cone D³.
- 15 The sprocket-wheel C has radiating at equal distances apart a series of arms c, having their outer ends slotted and each one provided in said slot with an antifriction-roller r to be received alternately into a slot f, which constitutes a hook of rocking connections f², which have side arms f³, by which they are pivotally mounted on the end of both the upper branch and the lower branch of the forked connecting-rod F. The outer end of each rocking connection f² is provided with a segment of gear-teeth that remain constantly in engagement with the teeth of a rack 2, that is secured to the interior surface of the sprocket-wheel casing 3 at its uppermost and lowermost points. Each rack 2 has cheek-pieces 4 to maintain each rocking connection in perfect alinement with its rack. The teeth of the rack and the teeth of the segments of gears are made of a special form, so that they will 30 "bottom" into each other, as said parts are the supports for the front ends of the forked connecting-rods and it is important that any rattling noise or vibration should be prevented.
- 35 40 To render the union of the rocking connection f² with the ends of the forked connecting-rod F substantially frictionless, each connection f² is provided with an arm f⁵ parallel therewith, that carries the grooved ballway, the balls, and the cones of ball-bearings. There is an inner cone f⁴, an outer cone f⁵, the head of which is received in part in a recess made into the inner face of the fork of the rod F, and a screw-bolt b², passing through 45 the cones and through the fork of the rod F, its head being countersunk into the outer face of said fork, and a retaining-screw f⁶ locks the bolt b². This construction of ball-bearings is repeated for each branch of the forked connecting-rods on both sides of the machine. The sides of the slot f of each rocking connection are lined with hard-steel face-plates f⁷, dovetailed in said sides.
- 50 55 The distance between the front ends of the branches of the forked rod F is maintained by a curved brace F², uniting said branches, and they are supported by the segmental gears f² and the latter by the racks 2, fastened to the casing 3. Said casing is firmly secured 60 to the pedal-sleeve of the frame and also to one of the side braces A². It has in its rear edge two openings for the passage of the

branches of the forked connecting-rod F, and said openings are rendered dust-proof and damp-proof by means of flexible diaphragms 70 5, of thin sheet-rubber, leather, or textile material preferably doubled upon itself and having its outer edge secured to the casing around each rod-opening and its center substantially clasping each branch of the forked connect- 75 ing-rod.

The pedals-shaft b is preferably made in two lengths diagonally cut at their inner ends and inclosed in a sleeve 6, screw-tapped with right and left hand screw-threads near its 80 ends and carrying cone-faced rings for ball-bearings, while a ring 7, L-shaped in cross-section, is employed for the other ball-bearing. Said ring 7 is screwed within the end of the crank-shaft sleeve of the frame by temporarily connecting it by means of a small pin (not shown) with the boss of the pedal-crank. After adjustment said ring, which has angular teeth on its inner edge, is locked by means of a small dog 8, that has a rectangular shoulder 9, made to pass partly through a slot in the sleeve. Said shoulder has a screw-threaded portion, upon which is placed a nut that clamps the dog 8 to the sleeve with its acute end in engagement with the serrations of the ring 7. The sprocket-wheel C is secured to the boss of the pedal-crank by means of two or three screws. The outer face of the casing 3 is closed with a thin metal disk g, having its periphery received in the 90 rabbeted edge of said casing and secured thereto with two or more screws.

The above description relates to the left-hand half of the driving mechanism; but the mechanism on the right-hand side is exactly 105 similar and consists of the forked connecting-rod G, the ends of which are provided with rocking connections, as f², each having a segment of gear in engagement with a rack and adapted for engagement with a sprocket-wheel having three arms at equal distances apart and provided with antifriction-rollers; but said sprocket-wheel is so timed relatively to the sprockets c of the wheel C as to be about thirty degrees in the rear of each one 110 of them.

The frame of the machine is provided with a forward brace A², as usual.

In the operation of the mechanism the rocking up and down and also longitudinally of 120 the rear end of the connecting-rod F or G causes the hooked connections at their front end to be rocked upon their rack-supports and their slotted end to be presented in the best positions to either receive one of the rollers r of the sprocket-wheel or to let one of 125 said rollers escape from engagement with the sprocket-wheels, so that the engagement of the parts will not cause any noise. As there must necessarily be some moments in which the rollers of the sprocket-wheels are not in 130 working engagement with the slots of the rocking connections f², (while entering and leaving them,) a duplication of the mechan-

ism is required to actuate the rear crank-axle during these intermediate movements. As there is only a little more than one roller of the sprocket-wheel or a portion of two rollers in engagement with the rocking connections on the ends of the forked connecting-rods, the friction is reduced to the minimum possible.

The diameter of the sprocket-wheels and the number of arms they are to carry or the diameter of carrying-wheels can be selected according to the speed of motion that may be desired.

Having now fully described my invention, I claim—

1. A mechanical movement consisting of an axle carrying two crank-pins, a forked connecting-rod mounted at each end upon each crank-pin and having at the opposite end two hooked connections pivotally mounted thereon, means as described to oscillate said hooked connections and sprocket-wheels having friction-rollers for engagement with the pivoted hooked connections substantially as described.

2. In a mechanical movement for bicycles, the combination of the axle of one of the carrying-wheels, two crank-pins carried by said axle, two branched connecting-rods mounted at one end upon each crank-pin and having at the opposite end two hooked connections pivotally mounted thereon, each hooked connection carrying a segment of teeth, and stationary racks for engagement with said segments of teeth, with sprocket-wheels for engagement with the pivoted hooked connections substantially as described.

3. In a bicycle the combination of the axle of one of the carrying-wheels, two crank-pins carried by said axle, two branched connecting-rods mounted at one end upon the crank-

pins and carrying at the opposite end two hooked connections pivotally mounted thereon, each hooked connection carrying a segment of teeth, and stationary racks having 45 side cheeks, with sprocket-wheels for engagement with the pivoted hooked connections substantially as described.

4. In a bicycle the combination of the axle of one of the carrying-wheels, two crank-pins 50 carried by said axle, two branched connecting-rods mounted at one end upon the crank-pin and carrying at the opposite end two hooked connections having bearing-carrying wings pivotally mounted upon the forked ends 55 of the connecting - rods, means as described to oscillate said hooked connections with sprocket-wheels for engagement with the pivoted hooked connections substantially as described. 60

5. In a bicycle the combination of the frame of the machine, the axle of one of the carrying-wheels, two crank-pins carried by said axle, two branched connecting-rods mounted at one end upon the crank-pins and carrying 65 at the opposite end two hooked connections pivotally mounted thereon, each hooked connection carrying a segment of teeth, sprocket-wheels for engagement with the pivoted hooked connections, and stationary casings 70 for the sprocket-wheels and for the hooked connections, racks secured within said casings, and flexible diaphragms secured to the casings and embracing the connecting-rods substantially as described. 75

In testimony whereof I affix my signature in presence of two witnesses.

HOSMER TUTTLE.
